CLAIM

The ornamental design for a robotic arm link as shown and described.

DESCRIPTION

FIG. 1 is a perspective view of a robotic arm link showing our new design;

FIG. 2 is a front view of the article of FIG. 1;

FIG. 3 is a rear view of the article of FIG. 1;

FIG. 4 is a top view of the article of FIG. 1;

FIG. 5 is a bottom view of the article of FIG. 1;

FIG. 6 is a left view of the article of FIG. 1;

FIG. 7 is a right view of the article of FIG. 1; and,

FIG. 8 is another perspective view of the article of FIG. 1.

1 Claim, 4 Drawing Sheets
